US0D1063067S

(12) **United States Design Patent** (10) **Patent No.:** **US D1,063,067 S**
(45) **Date of Patent:** **** Feb. 18, 2025**

(54) **ORAL IRRIGATOR**

(71) Applicant: **Wenzhou Xinan Electronic Technology Co., Ltd.**, Wenzhou (CN)

(72) Inventor: **Jili Chen**, Wenzhou (CN)

(73) Assignee: **Wenzhou Xinan Electronic Technology Co., Ltd.**, Zhejiang (CN)

(**) Term: **15 Years**

(21) Appl. No.: **29/937,603**

(22) Filed: **Apr. 16, 2024**

(30) **Foreign Application Priority Data**

Dec. 27, 2023 (CN) 202330859221.4

(57) **CLAIM**

The ornamental design for an oral irrigator, as shown and described.

DESCRIPTION

FIG. 1 is a front perspective view of an oral irrigator showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The dash-dash broken lines in the drawings depict the portions of the oral irrigator that form no part of the claimed design.

1 Claim, 8 Drawing Sheets
